ART OF REFINING HYDROCARBONS

Orin G. Kaasa, Munster, Ind., assignor to Sinclair Refining Company, New York, N. Y., a Corporation of Maine

Application August 15, 1931. Serial No. 557,250

1 Claim. (Cl. 196—47)

This invention relates to improvements in the cracking of refractory petroleum stocks to produce gasoline. Operations of this character are conventionally carried out by heating the refractory stock to a high cracking temperature while in transit through externally heated tubes serially connected to form a long continuous heating passage. The invention relates particularly to operations of this character.

10 "Coke", the solid decomposition product of the cracking reaction, deposited from a stream of relatively more refractory stock while passing through externally heated tubes in which it is heated to a cracking temperature, is hard 15 whereas a coke deposited from relatively less refractory stock under similar conditions is soft. In properly controlled operations, the rate of deposition of hard coke is very slow, much slower than the rate of deposition of soft coke usually 20 encountered, but eventually the accumulation of deposited coke requires termination of the operation to permit cleaning of the externally heated tubes. When cleaning becomes necessary, the hard coke deposited from refractory stock renders the cleaning operation particularly difficult.

According to this invention, however, the cleaning operation is simplified by initially circulating a less refractory stock through and heating it to a cracking temperature in the heated 30 tubes for a relatively short period, a minor part of the period of operation, before circulating the refractory stock therethrough. A thin deposit of soft coke is formed on the interior of the externally heated tubes during this initial 35 period of operation and the hard coke deposited from the refractory stock in the subsequent period of operation is deposited upon this previously formed deposit of soft coke instead of upon the interior of the externally heated tubes. 40 The soft coke itself does not involve any particular difficulty in the cleaning operation and, the thin deposit of soft coke being easily frangible, facilitates the removal, in the cleaning operation, of the hard coke deposited thereon.

45 The initial period of circulation of less refractory stock through the externally heated tubes is advantageously limited to avoid deposition during this period of a coke deposit itself sufficient to interfere with the operation. Usually, this initial period of operation is advantageously limited to about 1-6% of the total period of operation. Heavy virgin gas oil, 32-34 A. P. I. gravity gas oil for example, is an advantageous stock from which to form the initial 55 deposit of soft coke.

The accompanying drawing illustrates one form of apparatus, of the many forms of apparatus, in which the invention may be practiced. The apparatus illustrated in the accompanying drawing is of the general type described and 60 illustrated in Letters Patent Number 1,774,602, granted to Sinclair Refining Company September 2, 1930 on an application of E. W. Isom and Eugene C. Herthel.

Referring to the drawing, a stream of stock to 65 be cracked is forced, by means of pump 2, through a battery of serially connected tubes arranged in a heating furnace 1 into the vapor separating receptacle 3 from which vapors, including vapors of the cracked product, are taken off to a fractionating system, the stock to be cracked being heated to a cracking temperature during passage through the heated tubes. The stock to be cracked may be heated to a temperature approximating 850-950° F., for example, and is 70 discharged into the vapor separating receptacle 3. A pressure approximating 100-300 pounds per square inch, for example, may be maintained in the vapor separating receptacle 3, or a pressure approximating 1-10 pounds or a somewhat higher 75 pressure, for example, may be maintained in the vapor separating receptacle 3. The pressure on the hot oil products discharged from the battery of heated tubes may be maintained just sufficient to force these hot oil products into the vapor 80 separating receptacle 3, or this pressure may be maintained at some higher value, 300-600 pounds per square inch, for example, and the pressure on these hot oil products reduced as they are discharged into the vapor separating receptacle 3. 85 It is intended and will be understood that the foregoing details with respect to apparatus and operation are intended merely to illustrate one form of apparatus and operation in which the 90 invention may be embodied.

In practicing the invention in conjunction with the operation of the apparatus illustrated in the accompanying drawing, if the regular period of operation is 50-100 days (time on stream), for example, a heavy gas oil stock is 100 circulated through the battery of heated tubes for an initial period of 1-3 days, for example, before circulation of the refractory stock, a kerosene character stock or a light gas oil character stock, for example, through the battery of heated 105 tubes is begun.

The invention is useful particularly in conjunction with pressure distillation, or so-called "pressure shell" cracking operations in which vapor separation is carried out under super- 110

atmospheric pressure, in conjunction with pressure digestion, or so-called "reaction chamber", cracking operations in which vapor separation is carried out under lower pressure following digestion under higher pressure, and in conjunction with operations in which stock to be cracked is heated to a cracking temperature under high superatmospheric pressure and in which the hot oil products of this heating operation are separated into a vaporized fraction and an unvaporized fraction under lower pressure or so-called "pressure coil" cracking operations.

I claim:

In the cracking of refractory petroleum stocks
15 to produce gasoline in operations in which the

refractory stock is heated to a cracking temperature while in transit through externally heated tubes, the improvement which comprises initially circulating a stream of less refractory stock through and heating it to a cracking temperature 80 in the heated tubes for a minor part of the period of operation until a thin deposit of soft coke is formed on the interior of the tubes and thereafter circulating a stream of the refractory stock through and heating it to a cracking temperature 85 in the heated tubes whereby hard coke deposited from the refractory stock is deposited upon the previously deposited soft coke.
